CLAIM

(57) The ornamental design for a core barrel latch body, as shown and described.

DESCRIPTION

FIG. 1 is a front elevational view of a core barrel latch body showing my new design as used in a core barrel assembly; FIG. 2 is an enlarged exploded perspective view thereof; FIG. 3 is an enlarged assembled front elevational view thereof;

FIG. 4 is a right elevational view thereof;

FIG. 5 is a back elevational view thereof;

FIG. 6 is a left elevational view thereof;

FIG. 7 is a top plan view thereof; and,

FIG. 8 is a bottom plan view thereof.

The broken lines showing environment in the drawings are included for illustrative purposes only and form no part of the claimed design.
